UNITED STATES PATENT OFFICE

DENIS REMY CAMPENS, OF BERCHEM-ANTWERP, BELGIUM

HELICOPTER

Application filed March 3, 1932, Serial No. 596,527, and in Belgium April 17, 1931.

The present invention relates to the improved construction of helicopters, i. e. aviation apparatus heavier than air, capable of leaving a spot on the ground solely by their own means on board, to rise in the atmosphere and return to the same spot on the ground, all these movements being performed on a vertical line passing through the said spot.

In order to give a more practical character to the apparatus, it is desirable to add to the same certain devices enabling it to perform movements according to the three dimensions of space. The great difficulty presented in embodying a helicopter is its stability. Consequently, the greatest care is required in order to obtain good stability as well in the shape as in governing.

The invention will be described hereafter with reference to the accompanying drawings, in which different forms of embodiment have been illustrated.

Figs. 1, 2 and 3 are respectively a plan view, a front view and a side view of a helicopter in accordance with the invention;

Figs. 4 and 5 are a partial plan view and a partial side elevation showing details of the apparatus;

Figs. 6, 7 and 8 are front elevations of further forms of embodiment of a helicopter;

Figs. 9, 11, 12, 13 and 14 refer to calculations cited in the description;

Fig. 10 is a partial plan view of a lifting propeller used with the helicopter;

Fig. 15 shows a diagrammatic composition of driving and clutching means securing stability in the longitudinal direction;

Figs. 16 to 20 illustrate diagrammatically some details of the mechanisms used in the apparatus;

Figs. 21 and 22 illustrate respectively a front elevation and a plan view of a further improved form of embodiment of the helicopter;

Fig. 23 is a diagrammatic composition of driving and clutching elements used for securing longitudinal stability.

With reference to the drawings, the helicopter has a cross-shaped fuselage 1, 2, 3, 4, 50 constituted with trellis-work girders. At

each end 3 and 4 are mounted balancing frames 5 and 6. These frames are capable of oscillating in transverse direction about their horizontal axis, between the front and rear end plates of the girder 3-4. Two connecting rods 7 and 8 each join the upper edge of one of the balancing frames 5 to the lower edge of the opposite balancing frame 6. Each balancing frame carries in its lower part a star-shaped air-cooled motor 9 and 10, the vertical shafts of which are extended upwards and on which are mounted the horizontal lifting propellers 11 and 12, rotating in opposite directions the one to the other.

Close above each motor 9 and 10 and on their extended axles, are keyed small fans ensuring the cooling of the motors. The motor shafts 13 and 14 are also extended downwards and engage with bevel gear boxes 15 and 16, from which the shafts protrude again 70 and carry at their lower ends horizontal fly-wheels 17 and 18, the latter rotating in opposite direction to the coupled lifting propellers, thus absorbing the gyroscopic efforts.

Each balancing frame carries at its lower end a wheel 19 and 20, provided with a shock-absorber 21 and 22. At the front end of the girder 1-2 is fixed the driving motor 23.

On the front shaft of the motor 23 is keyed a tractor propeller 24 preferably with four blades.

A horizontal propeller 25 is mounted at the rear of the pilot's seat 26. The front and rear ends of the cross-shaped fuselage are also provided with a wheel 27 and 28 and a shock-absorber 29 and 30.

The balancing frames can, by means of a set of levers and rods be wedged at 90° on 90 the cross-shaped fuselage.

For the purpose of clearness of Figs. 1, 2 and 3, the additional Figures 4 and 5 show the disposition of the lateral ailerons 31, of the horizontal rudder 32 and of the vertical 95 rudder 33.

In the embodiment illustrated in Fig. 6, the motor frames are fixed and converge to one another in the upward direction. The lifting propellers will thus maintain the 100

same angle with a horizontal line passing through the transverse girder. In this case, the gear boxes 15 and 16, the fly-wheels 17 and 18 and the connecting rods 7 and 8 are 5 eliminated. The ailerons 31 can be placed beneath the transverse girder and pivot about a middle horizontal axis in both directions, front or rear, and can even be placed in a vertical plane.

10 Fig. 7 shows an apparatus in which the lifting motors 34 are erected vertically in the middle of the longitudinal girder and in front of the transverse straight girder. The motor power is transmitted to the lifting propellers by means of geared bevel-wheels 35 and 36. For clearness of the drawing, the motor and the front propeller are not shown.

15 In Fig. 8, which is the same as Fig. 7, the transverse girder is not straight but formed 20 with two parts inclined to each other in the upward direction. This model gives the best working solution and a preferred form of construction is further illustrated in Figs. 21 and 22.

25 The advantage secured by constructions according to Figs. 1 to 3, consists in the fact that the lifting propellers take a variable balanced position at each moment, due to the variation, intentional or accidental, of the 30 center of pressure of each lifting propeller. On the other hand, the apparatus according to the alternative forms is of a stronger construction, less heavy, gives less vibrations and is submitted to less harmful efforts, is 35 less subjected to gyroscopic effects and can admit a greater horizontal translation; owing to this fact, it will be more practical, more sure and easier to control.

40 The ailerons will only be used for horizontal flight, together or not with the lifting balancing propellers. The horizontal rudder is also employed only for horizontal motion.

45 The profile, the pitch, the shape, the dimensions, the number and kind of coupling of the blades forming the lifting propellers are all factors influencing the aerodynamic efficiency of the apparatus.

50 The lifting propellers for an apparatus operating at a fixed spot or in simple vertical translation, and the lifting propellers for an apparatus capable of moving according to the three dimensions of space will not be the same.

55 In the first case, the lifting propellers will only be submitted to one velocity: the rotation speed (the apparatus being in free space with no or nearly no wind in comparison with the rotation speed), and in the second 60 case, the horizontal translation velocity, which is added and may attain appreciable values in comparison with the rotation speed; by this fact, the conditions of the lifting propellers are changed from one case to 65 the other.

In the case of the lifting propellers in a simple vertical translation, the best raising qualities correspond to variable inclinations of each blade and this from the center (motor shaft) until the periphery, because the speed of each blade varies from 0 in the center to $2\pi rn$ at the periphery. The angle fixing the inclination angle of a lifting propeller in vertical translation is given by the angle α (Fig. 9), in which:

AB is the rotation plane;

V_1 = vertical translation velocity;

V_2 = plane rotating velocity;

V = resulting velocity;

β = pitch of the plane;

$\beta - \alpha$ = incidence angle of the vertical translation.

In Fig. 9:

$$\operatorname{tg}\alpha = \frac{\sin \alpha}{\cos \alpha} = \frac{V_1}{V_2}$$

Now, in the center $V_2 = 0$
resulting in

$$\operatorname{tg}\alpha = \frac{V_1}{0} = \infty$$

resulting in $\alpha = 90^\circ$
at the periphery $V_2 = 2\pi rn$
resulting in

$$\operatorname{tg}\alpha = \frac{V_1}{2\pi rn}$$

Thus in this case the lifting propeller will be at 90° near the vertical root and reduce progressively until the periphery, where it approaches 0° , thus nearly horizontal.

By a lifting propeller in horizontal translation, these conditions change, because horizontal speed intervenes and must be taken into account.

In this case, analogous to the one of a fixed aeroplane wing, a uniform angle near to 10° is required along the whole length of the blades, so as to obtain a maximum thrust with a minimum trail.

A right intermediate choice must be taken 110 between these two solutions. The blades of the lifting propellers approaching the shape of driving propellers of an aeroplane, give a good solution. Being intended for rotating at high speeds and in order to neutralize by 115 this fact effects of centrifugal force, the blades will preferably be made of one single piece of wood or light metal.

The velocity of the blades along their longitudinal axis varies, as explained above, 120 from a minimum 0 at the root, to a maximum $2\pi rn$ in the periphery. In consequence, the maximum value of the thrust $K_z SV^2$ is theoretically situated at the periphery. Practically, this maximum value is found to the rear at about $\frac{2}{3}$ of the length of the blades at their root. Therefore, it is advantageous to give to this part of the lifting propeller greater surface, so as to obtain a maximum thrust for a given lifting surface. The tips 130

near the periphery will be rounded and cut away, in order to reduce at the rear edge of the eddy currents harmful to the good aerodynamic efficiency of the blades. The inclination of the blades on the horizontal line will be nearly constant along their whole length. As in the case of an aeroplane wing, the elongation must also be taken into account. A great elongation gives the best results; unfortunately, this would lead us to blades of too great a diameter, which would consequently, at great speeds, undergo too heavy a strain. An elongation from four to five times is to be recommended.

As a result of all these considerations, the blades of a helicopter made to move according to the three dimensions of space will have a similar shape to the one of Fig. 10.

The quantity of blades per lifting propeller as well as the coupling system of same play an important part in the aerodynamic efficiency of the planes. The best solution for a helicopter intended for simple vertical translation is a lifting propeller with two blades, giving the least interaction, but the lifting propeller with four blades gives more stability, a better distribution of the load per area unit and planes of less diameter.

Every helicopter must at least have two lifting propellers rotating in opposite directions the one to the other, in such a way that the reaction torques will be mutually neutralized, or else an additional device repudiating the torque. Without such device, the apparatus would turn round itself. The two lifting propellers rotating in opposite directions may be on concentric shafts or side by side. Although concentric lifting propellers give less volume to the apparatus, the system side by side is preferred, as it causes less interactions and gives in consequence superior raising quality.

With relation to lateral stability, the lifting propellers act both as lifting devices and lateral balancers.

Lateral stabilizing is obtained by coupling a separate motor to each lifting propeller, with separate working.

In this way, when one of the lifting propellers lowers or rises, and by this fact inclines the apparatus in lateral direction, the rotation velocity of the motor coupled to the lifting propeller in question will be increased or decreased, in such a way as to raise or reduce the thrust. Each lifting propeller operates levers of nearly equal length, but the one operating with greater force brings back the apparatus to its horizontal position. As the thrusts are equal to $K_2 SV^2$, and $K_2 S$ being nearly identical for both lifting propellers, when doubling the speed of one of the motors, a thrust which is four times greater would be obtained at this side. In simple vertical translation with horizontal wind and in horizontal translation (results are nearly

the same) the relative velocity of each blade of a lifting propeller differs periodically at every revolution, as is shown in Figs. 11 and 12, in which:

v = horizontal translation velocity

V = rotation velocity.

70

Relative resultant velocity

in point A = $V + v$

in points B and D = $\sqrt{V^2 + v^2}$

in point C = $V - v$

in point E = $\sqrt{V^2 + v^2 + 2Vv \cos \beta}$

in point F = $\sqrt{V^2 + v^2 - 2Vv \cos \beta}$

75

thus with a maximum in A with $V + v$ and a minimum in C with $V - v$. The centers of pressure are consequently eccentric and do not correspond to the center O of the lifting propeller (Fig. 13).

For A and C the center of pressure will be in G.

For D and B, being alike, it will be in the center O.

For E and F, in the point H.

Thus in one complete rotation the center of pressure will have made a circumference with diameter

$$OG = \frac{DVv}{V^2 + v^2}$$

95

D = diameter of the lifting propeller.

For two lifting propellers coupled side by side, rotating at a uniform speed and in horizontal translation the general resultant for a pressure of the two lifting propellers will pass along the symmetry line of the apparatus (vertical line passing through the center of symmetry).

If intentionally or accidentally the rotation speed of one of the lifting propellers is changed and does not correspond any longer to the other, the resulting force will no longer pass along the symmetry center and the apparatus will incline to the side of less speed. In Fig. 14 comparison is made in case of accidental decrease of speed or pressure of one of the lifting propellers in an apparatus with straight motor axes (plain lines) and in an apparatus with converging motor axes (dotted lines).

100

105

110

115

v = velocity in accidental decrease	P = resultant	Apparatus with straight axes.
v^1 = unchanged velocity	P_1 = resultant	
v^2 = balancing velocity	P_2 = resultant	Apparatus with converging axes.
v^3 = velocity in intentional decrease	P_3 = resultant	
v^4 = velocity in accidental decrease	P_4 = resultant	Apparatus with converging axes.
v^5 = unchanged velocity	P_5 = resultant	
v^6 = balancing velocity	P_6 = resultant	
v^7 = velocity in intentional decrease	P_7 = resultant	

120

125

It must be noted that with further increases of rotation speed the center of pressure will approach the center O of the lifting propeller, owing to the formula:

$$\frac{DVv}{V^2 + v^2},$$

as stated above.

130

The combined action of pressure increase on the plunging side (intentional increase of the rotation speed of the plunging motor) and decrease of pressure at the rising side 5 (intentional decrease of rotation speed of the rising motor) returns the apparatus instantaneously to its horizontal balance position.

The results for an apparatus with straight or oblique axes are nearly the same, the 10 forces P_1 and P_3 and their lever arms OC and OB being nearly equal, but in the case of an apparatus with converging axes, the pressure tends to oppose itself to the started movement and approaches more and more 15 to the vertical line, while in the apparatus with straight axes, the same tends to remain longer inclined and even to permit to the apparatus to start an oblique lateral gliding flight.

20 When the apparatus puts itself laterally oblique, it will tend to start a gliding flight in the direction of inclination.

The apparatus with converging axes has the great advantage to prevent or at least to 25 absorb or retard this gliding flight, thanks to its great stability of shape, due to the converging of its motor shafts. The plunging lifting propeller receives in fact a higher thrust than the other and tends to right the 30 apparatus automatically.

Thus in case of lateral inclination, these 35 different factors decreasing its motion will permit the pilot to operate in due time the plunging motor, so as to increase its speed and at the same time decrease the speed of the rising motor, so as to bring back the apparatus to its horizontal position.

The gliding flights will equally be absorbed by the great inertia possessed by the 40 apparatus itself.

In horizontal motion, longitudinal balance can be obtained by the action exerted by the rear horizontal plane 32, Fig. 4.

In simple vertical translation, this 45 stability is secured by a horizontal propeller operated (for the sake of weight economy) by the front tractor motor. By means of a lever and sliding change speed pinions, this propeller can rotate either in one or in the 50 other direction, causing in this way either an upward thrust or a downward thrust, according to the direction of rotation.

The front driving propeller 24 (Fig. 15) is 55 coupled by its shaft to the motor 23, by means of a usual clutch system 37. The motor shaft carries at its rear end a gear-wheel 38 permanently meshing with another wheel 39 keyed on shaft 40. This shaft 40 carries also two other gear-wheels 41 and 42. The 60 wheel 42 meshes permanently with wheel 43 keyed on shaft 44. The lever 45 pivoting about a point 46 is provided with a latch spring lever 47, which can be stopped at a notch of a toothed sector 48. The operating 65 of the lever either to the front or to the rear

(direction of arrows 49 and 50) draws with it two rods 51 and the sleeve 52 with guide slot (sliding on shaft 53). On the sleeve 52 are keyed two gear-wheels 54 and 55. The lever 45 slides and draws with it the sleeve 52 by means of a second concentric guided sleeve 56, between two abutments 57 (for details see Fig. 16) and can place either the wheel 54 and 41 or 55 and 43 in front to one another. The shaft 53 transmits the motor movement to a bevel gear 58 and 59, the latter transmitting the rotation to a horizontal propeller 25 keyed on shaft 60.

The two rods 51 transmit a to and fro movement to two parts 61 covered with asbestos and used as a brake (Prony type) on shaft 60, at each change of rotation of this shaft (for details see Fig. 17).

At each change of direction of rotation of the horizontal propeller, the motor shaft is uncoupled from the motor by means of an uncoupling system 62. The uncoupling movement is transmitted by the lever 45 to a plunger 63 acting on the retaining spring of the clutch (not shown in the figure so as not to interfere with the clearness of the drawing) by means of the rod 64, the crank lever 65, the rod 66 and the slide block 67.

The movement of the slide block is adjusted in such a way that the wheel 54 or 55 is already slightly meshing with respectively the wheel 41 or 43 before the clutch 62 has worked, and reciprocally by uncoupling.

Beside the usual instruments as altimeter, revolution indicator, etc., the steering cabin contains:

- (1) a starting lever for each motor (thus three starters);
- (2) three accelerators (one for each motor);
- (3) a "stick" for operating the horizontal rudder and the planes;
- (4) a rocking lever operating the rudder;
- (5) a keying lever for the balancing frame;
- (6) a steering lever for the longitudinal lifting propeller;
- (7) a lever for coupling and uncoupling the front driving propeller.

The steering 5 is only used in certain cases, such as free fall, etc., for an apparatus with moving balancing frames.

With reference to the automatic coupling and uncoupling of the lifting propellers (Figs. 18 to 20), each lifting propeller turns loose on its shaft 68, by means of a ball bearing 69 between them. Each lifting propeller is provided at its lower base with a coaxial cup 70, fixed to the lifting propeller and which ends beneath in a straight gearing crown 71 with deep recesses. The joining of the cup with the lifting propellers will be made by means of a spring between them, so as to absorb the shock at the moment of coupling the planes.

Beneath the cup, the motor shaft carries

70

four feathers 72, fixed on four sides, in which articulate four small levers 73 ending in four counterweights 74.

With stopped motors, the lifting propellers 5 rotate freely about the motor shaft. When the motor runs, because of centrifugal force, the four counterweights deviate from their vertical position of rest and place themselves horizontally, each little gap engaging with a tooth of the crown gear and drawing with it the lifting propeller in the rotation movement of the motor shaft (Figs. 19 and 20).

This device permits:

(1) to descend in free fall, the lifting motors stopped. The apparatus descends as a parachute, the lifting propellers rotating freely on their shaft with a speed which accelerates with acceleration of the falling speed. By acceleration of the rotation speed 20 the thrust is increased and falling speed by this fact is decreased (lifting propellers uncoupled);

(2) to fly with autorotation;

(3) to fly in horizontal translation with the front driving motor stopped and lifting propellers coupled. In fact, when inclining the apparatus rearwards and forming an oblique with the horizontal line, the horizontal composing force of the reaction on the lifting propeller produces forward drive.

The obliquity is obtained in this way through the horizontal rudder.

The following operations are to be done in case of break down of one or more of the motors:

(1) Break down of the front driving motor:

Flight may be continued in horizontal translation by flying with the apparatus in obliquity to the horizontal.

(2) Break down of lifting motors:

Flight may be continued in autorotation.

(3) Break down of the three motors:

Descent may be done:

3a either in oblique, while steering to fixed spot, in autorotation, due to the acquired gliding flight speed;

3b or else along a vertical line, the apparatus falling as a parachute.

A further form of embodiment of the helicopter has been illustrated in Figs. 21 and 22. The helicopter being intended for moving in vertical and horizontal directions, will have the most advantageous profile when the general shape of the apparatus will be that of a convexo-convex lenticular figure, this shape giving the least resistance with respect to the directions of movement referred to hereabove.

An apparatus of this shape will have lifting propellers 75, a vertical rudder 76, air-cooled motors with fans 77 for driving the lifting propellers, tractor propellers 78, ailerons 79, bevel gear transmissions 80 for the lifting propellers, a motor 81 for the tractor propellers,

bevel gear transmissions 82 for the tractor propellers 78, seats 83 for the pilot and conveyor, a horizontal rudder 84, stabilizing propellers 85 at the end of the fuselage, one above and the other underneath the rudders, said stabilizing propellers being adapted to move in opposite directions. Fuel and oil will be advantageously stored in the tank 86.

The three motors for this apparatus will be of light construction.

The lifting propellers will be made for instance from multiple layer wood or from a resistant and light metal. These lifting propellers will be constructed similar to the tractor propellers, the pitch being variable and having an angle of $90^\circ > x > 0^\circ$. Otherwise the inclination of the blades can be uniform or constant from the center to the periphery. Automatic clutch devices can be provided for driving the propellers.

This aeroplane can be provided with one or two tractor propellers in front of and underneath the lifting propellers. When moving in vertical direction, the ailerons and horizontal rudder can be placed in a vertical plane, in order to reduce resistance of the atmosphere.

Longitudinal stability during vertical flight is secured by means of two separate propellers similar to the lifting propellers, but of reduced dimensions, the one being arranged above the fuselage and the other underneath, close to the rudders. These stabilizing propellers are separately controlled by means of a lever and can rotate in opposite directions so that, as a technical effect, one of these propellers will lift the fuselage and the other draw it downwards.

The controlling device as illustrated in Fig. 23 comprises: a driving shaft 87 from the front tractor motor, gear transmissions 88 and 89, clutches 90 for the stabilizing propellers, the controlling lever 91 for said clutches 90, the lever moving along a toothed sector 92, friction brakes 93, movable elements 94 cooperating with said brakes, bevel gears 95 for driving the stabilizing propellers 96 and 97. The tractor propeller can be unclutched.

I claim:

1. A helicopter comprising in combination: a cross-shaped fuselage, an oscillating frame on each side of the fuselage arranged at each end of the transverse cross member, the oscillation axis of said frames being substantially horizontal and parallel to the longitudinal cross member, a lifting propeller at the top side of each oscillating frame, a separate motor in each oscillating frame for driving the lifting propeller, a fly-wheel in each oscillating frame driven by said motor, a tractor propeller at the front end of the longitudinal cross member, a motor driving the tractor propeller, ailerons underneath the transverse cross member, a horizontal and a vertical

- rudder, a stabilizing propeller at the rear end of the longitudinal cross member, means to drive the last-mentioned stabilizing propeller, a landing structure comprising wheels and shock-absorbing devices, automatic coupling system of the two lifting propellers, and means to control the operation of the lifting, stabilizing and tractor propellers, substantially as set forth.

2. A helicopter comprising in combination: a cross-shaped fuselage, a fixed frame on each side of the fuselage and arranged at each end of the transverse cross member, contained in the horizontal plane of the longitudinal cross member, a lifting propeller mounted at the top side of each lateral cross end structure, the shafts of said lifting propellers being inclined to each other in an upward and converging direction, a separate motor for driving each lifting propeller and located at each lateral cross end structure, a tractor propeller at the front end of the longitudinal cross member, a motor driving the tractor propeller, ailerons underneath the transverse cross member, a horizontal and a vertical rudder, a stabilizing propeller at the rear end of the longitudinal cross member, means to drive the last-mentioned stabilizing propeller, a landing structure comprising wheels and shock-absorbing devices, automatic coupling system of the two lifting propellers, and means to control the operation of the lifting, stabilizing and tractor propellers, substantially as set forth.

3. A helicopter comprising in combination: a cross-shaped fuselage, a fixed frame on each side of the fuselage and arranged at each end of the transverse cross member, contained in an oblique plane to the horizontal plane of the longitudinal cross member forming a V-shaped construction, a lifting propeller mounted at the top side of each lateral cross end structure, the shafts of said lifting propellers being inclined to each other in an upward and converging direction, a separate motor for driving each lifting propeller and located at each lateral cross end structure, a tractor propeller at the front end of the longitudinal cross member, a motor driving the tractor propeller, ailerons underneath the transverse cross member, a horizontal and a vertical rudder, a stabilizing propeller at the rear end of the longitudinal cross member, means to drive the last-mentioned stabilizing propeller, a landing structure comprising wheels and shock-absorbing devices, automatic coupling system of the two lifting propellers, and means to control the operation of the lifting, stabilizing and tractor propellers, substantially as set forth.

4. A helicopter comprising in combination: a cross-shaped fuselage, a fixed frame on each side of the fuselage and arranged at each end of the transverse cross member, contained in an oblique plane to the horizontal plane of the longitudinal cross member forming a V-shaped structure, a lifting propeller mounted at the top side of each lateral cross end structure, the shafts of said lifting propellers being inclined to each other in an upward and converging direction, a separate motor for driving each lifting propeller and located at the top side of each lateral cross end structure, a motor driving the tractor propeller, ailerons underneath the transverse cross member, a horizontal and a vertical rudder, a stabilizing propeller at the rear end of the longitudinal cross member, means to drive the last-mentioned stabilizing propeller, a landing structure comprising wheels and shock-absorbing devices, automatic coupling system of the two lifting propellers, and means to control the operation of the lifting, stabilizing and tractor propellers, substantially as set forth.

5. A helicopter comprising in combination: a cross-shaped fuselage, a fixed frame on each side of the fuselage and arranged at each end of the transverse cross member, contained in an oblique plane to the horizontal plane of the longitudinal cross member forming a V-shaped structure, a lifting propeller mounted at the top side of each lateral cross end structure, the shafts of said lifting propellers being inclined to each other in an upward and converging direction, a separate motor for driving each lifting propeller and located in the centre of the cross-shaped fuselage, transmission gears for driving the lifting propellers by said motors, a tractor propeller at the front end of the fuselage, a motor driving the tractor propeller, ailerons underneath the transverse cross member, a horizontal and a vertical rudder, a stabilizing propeller at the rear end of the longitudinal cross member, means to drive the last-mentioned stabilizing propeller, a landing structure comprising wheels and shock-absorbing devices, automatic coupling system of the two lifting propellers, and means to control the operation of the lifting, stabilizing and tractor propellers, substantially as set forth.

In testimony whereof I signed hereunto my name.

D. R. CAMPENS.
